BELL GASHOLDER

Konrad Jagschitz, Mainz, Germany, assignor to
 Maschinenfabrik Augsburg-Nürnberg A. G.,
 Nuremberg, Germany, a corporation of Germany

Application April 7, 1931, Serial No. 528,279
 In Germany April 16, 1930

7 Claims. (Cl. 48—176)

The dry or waterless gas holders known in practice consist of a fixed vertical tubular shell of circular or polygonal transverse section in which a closing disk is vertically movable. In contradistinction thereto the present invention relates to a dry or waterless gas holder, the chief characteristic feature of which comprises a vertically movable bell capable of rising and falling according to the amount of gas contained in it, the bell being arranged upon and confining a stationary bottom, the rim of which lies close to the inner surface of said bell and engages a packing means arranged between the bell and bottom. The packing means may be of any desired description; they may be completely dry, or a suitable substance, such as a liquid or a fat or grease of a suitable consistency, or the like, may be used.

This arrangement presents over the known disk gas holders, and also over the telescopic gas holders with sliding packing, as of late proposed, a number of very important advantages, which will be pointed out hereinafter.

One of the disadvantageous features of the abovementioned telescopic gas holders, as well as of the disk gas holders, resides in the fact that the support of the packing or sealing means is movable; besides, with disk gas holders, the seal is accessible only with difficulty, as, in order to reach it, it is necessary to ascend the shell at its outer surface and to descend at the inner surface thereof. With the present improved construction, however, the packing or sealing means remain always at the same place and are easily accessible, as are also the guide rolls or the sliding cheeks for the immovable bell.

Another advantage of my invention, especially over the disk gas holders, resides in the fact that enclosed spaces, in which in case of leakage explosive mixtures can form, are obviated.

A particularly important advantage of the invention is that the stresses arising in the gas holder walls are by far smaller than in the known forms of gas holders, and the walls can be designed, therefore, considerably lighter than in the known constructions.

The improved gas holder can be designed with a circular section, as well as with a polygonal one.

The invention is illustrated diagrammatically and by way of example on the accompanying drawings on which Figure 1 is an axial section through a gas holder designed according to the invention; Figure 2 is a similar view, showing a disk gas holder of known design for the sake

of comparison; Figures 3, 4, 5, 6 and 7 are views similar to Fig. 1, showing, however, modifications; Figure 8 shows a detail of the wall structure, and Figure 9 is intended to aid in understanding the manner in which the gas holder is erected, as all fully described hereinafter.

Referring to Fig. 1, *a* denotes the bottom which is carried by a suitably designed structure or frame *b*. The bottom *a* may be provided with a closable opening for the escape of water of condensation from the interior of the holder. It is of advantage to arrange this opening at the rim of the bottom, and it is also practical to provide heating means around the said rim in order to melt ice that may have formed during frost. To prevent the ice from adhering to the inner surface of the shell, irrigating devices *q* (Fig. 4) may be provided, by means of which tar oil is distributed around the circumference of the shell.

Above the bottom is the bell *c* which is sealed in known manner at the places *d* with respect to the bottom *a* and is guided therewith. From the centre of the bottom there extends upwardly the guide tube *f* which is firmly connected with the bottom and the upper end of which constitutes a guide member for the bell *c*. A packing *g* provided at this place, i. e. between the tube *f* and the centre of the roof of the bell and attached to the latter seals such place.

The chief advantages which the new arrangement and combination of parts presents can well be ascertained from Fig. 1. The packing *d* is and remains always at the same place and is easily and conveniently accessible from the inner side of the frame, it being, of course, understood that it is designed in an appropriate manner. The second advantage, viz.—the obviating of spaces in which explosive mixtures can form, can be attained by designing the frame *b* as an open structure and by letting the guide tube *f* remain open at both ends so that the space below the bottom *a* is continuously ventilated. This very good ventilation permits the closing of the space below the bottom *a* to a greater or lesser degree, and to employ it for any suitable purpose, but it is in such a case advisable to provide one or more apertures in the wall surrounding said space so as to allow of the ventilating air streaming through the said space.

The third chief advantage will appear from a comparison of Fig. 1 with Fig. 2 in which a disk gas holder of known design is shown. The vertically movable disk is guided by rolls *h*. The moment counteracting the tipping over of the disk

has in this case only the comparatively short lever arm i wherefrom result relatively high roll pressures, and the disk, as well as the shell enclosing it, must be designed in correspondence 5 with these pressures. In contradistinction thereto, with the present improved gas holder, the closing bell is guided on the one hand by rolls m which are vertically guided, and on the other hand by rolls provided in the proximity of the 10 upper packing. The moment counteracting the tipping over of the bell has in this case the moment arm k which, as can be seen at once, is a multiple of the corresponding arm in Fig. 2, and the pressures arising in the guides at the bearing 15 are correspondingly reduced.

The more favorable action of the forces in the improved gas holder is due also to the following circumstance: If the shell is computed according to the old system, there must be chosen as 20 basis for the computation of the wind pressure the assumption that the disk is in its lowermost position, as the conditions are then the most unfavorable. This will be clear when it is considered that when the closing disk is in its highest 25 position, nearly the entire shell will be subjected to the action of the inner gas pressure and is thereby stayed in radial direction. If, however, the closing disk is in the low position, such staying no longer exists. Now, as the shell 30 must stand the wind pressure in every position of the disk, the computation must be based upon the lowermost position of the disk, and the staying effect of the inner gas pressure cannot be taken advantage of in any way. These matters 35 are by far more favorable with the present improved gas holder. In this construction the upper part of the bell, insofar it is located above the bottom a , is always subjected to the action of the inner gas pressure, the dead weight of 40 the freely suspended shell, together with any loading weights that may be affixed to the lower rim of the shell, serving for increasing the gas pressure. The staying action of the inner gas pressure can, thus, be taken advantage of fully 45 in computing the bell and determining its dimensions. Those parts of the shell that lie below the bottom a when the shell is in its lowermost position and which, therefore, can no more be stayed by the inner gas pressure find, with the 50 present improved holder, the necessary support at the supporting structure b which can be provided for that purpose with sliding cheeks x (Fig. 5), which may be adjustable, if desired. In view of these favorable conditions, computation 55 shows considerably lower weights for the construction of the shell, including the sheet metal members, than is the case with the known constructions.

The supporting structure b carries at its top 60 the rigid bottom a by which all wind pressures are uniformly distributed upon the individual supports and fields constituting said structure, the latter thus requiring a minimum amount of material for its construction. That part of the bell which at any moment is disposed below the 65 bottom is protected at its inner surface from being unfavorably influenced by the weather, and there is also no danger that water of condensation will collect at such downwardly projecting inner 70 wall of the bell, no ice being formed on such wall during frost because the space below the bottom is in continuous communication with the outer air.

A simplified construction of the improved gas holder is shown in Fig. 3 in which the guide

tube f has been omitted. In order to prevent the bell nevertheless from tipping over, the bell shell is elongated downwardly or at least provided with downwardly directed extensions, so that when the bell is in its uppermost position, 5 as in Fig. 3, the moment arm k^1 is available to resist the tipping action of wind pressure. It is in this case not necessary to make the bell portion k^1 plate-webbed, as shown in the right hand 10 half of Fig. 3, but such portion may be designed 15 in the manner shown at k^2 in Fig. 3 in which k^2 denotes a guide structure provided with guide rolls m^1 arranged at the lower end of said structure.

In Fig. 4 the guide tube f extends down to the 15 ground and can be used in this case as a central support for the bottom a . If it is to be used also in this case as a ventilation tube, inlet openings n must be provided in its wall.

In the further modification shown in Fig. 5 the 20 tube f which is in this case not longer than in Fig. 1 is supported by a conical structure, this structure being supported in turn by the structure b , as shown. This constructional form presents over that shown in Fig. 4 the advantage 25 that the gas holder is practically nonsensitive at all to settling of the ground, because the bottom a is not in the least subjected to distortions of any kind.

The invention presents also certain other advantages, of which the most important are the 30 following:

The arrangement and combination of the parts render possible a considerable reduction of the 35 foundation. With the known construction the inner gas pressure acts directly upon the ground. With the present invention, however, the gas pressure is transmitted to the foundation by the intermediary of the bottom a and the structure b . With the known constructions the windward 40 forces tend to lift the foundation upon the wind side, whereas with the present improved construction this detrimental effect is compensated at least partly, and generally wholly, by the gas pressure, in consequence whereof the foundations 45 can be by far smaller. If the bell is completely emptied its top contacts with the bottom a whereby a substitute for the action of the gas pressure is afforded, and such supporting contact affords the further advantage that the shell 50 of the bell is freely suspended and is, therefore, not subjected to a bending stress.

The invention presents also the further advantage 55 that the gas connections can be arranged outside the holder at favorably located places and are easily accessible; separate shafts for such purpose can thus be dispensed with. This is a requirement, upon whose fulfillment very great value is placed in practice, for instance in the case of heavy gases, such as blast-furnace 60 gases.

Also certain other constructional forms are 65 possible. Thus, for instance, the bottom a can be arranged at a lesser height than in the examples shown in Figures 1, 3, 4, 5 and 6; it may even be arranged practically flush with the ground, and an annular or tubular pit for the reception of the bell may be provided below the thus arranged bottom. The entire shell may be 70 designed in known manner as a spirally-shaped shell; if, on the other hand, the shell is to be prevented from rotary movement, known means may be used for this purpose, for instance by arranging the vertical rivet seams of the shell in the manner shown in Fig. 8 in which r and r^1 are 75

the sheet-metal members connected with one another by rivets *t* by the intermediary of flat iron bars *s* and *s*¹. The inner ends of the rivets which are located opposite the packing are countersunk so that this face of the bar *s* is flat. This bar constitutes the guiding member that keeps the shell from rotary movement.

The weights *l* (Fig. 1) that consist preferably of concrete may be replaced by one or more bodies of water, as shown in the constructional form illustrated in Fig. 6, in which the top of the bell is designed as a flat basin *o* which is preferably subdivided by vertical partition walls which assist in retaining the water in said basin.

15 It is also possible to design the gas holder as a telescopic holder, as in Fig. 7. Building the gas holder in this manner presents the advantage that the supporting structure can be lower than in the other cases, in consequence whereof the 20 entire height of the holder is reduced, which in turn yields a shorter moment arm for the wind forces. On the other hand, the drawback must be considered that only one (*d*) of the sealing place is stationary, whereas the other seal or 25 seals (*p*) move vertically with the telescoping sections. It will be understood that suitable means (not shown) will be provided to limit the movement of the intermediate gas holder sections between the bottom of the gas holder and 30 the bell to prevent disengagement of such intermediate members at their seals in the collapsed condition of the gas holder.

In order to prevent excessive lifting of the bell, abutment members *f*' may be provided at suitable 35 places, for instance at the tube *f* or at the supporting structure *b* as shown at *b'*, *b''* (Figs. 3 and 7), these abutment members limiting the upward movement of the bell; their arrangement may be such that they become active only after 40 the bell has formed a small gap either above the bottom *a* or at the tube *f* so that the excess of the gas can escape. It is obvious that in such a case the gas escapes freely into the open air without any possibility of doing damage. The abutment 45 members may, however, be arranged also in such a manner that the gas cannot freely escape but that an increase of the pressure in the bell takes place. The tensile forces then arising compensate one another in the structure. In order to 50 prevent surpassing of the admissible highest pressure, safety valves *c'* (Fig. 3) of any approved design may be provided and mounted in known manner.

The shell can, of course be provided with a 55 separate outer guide structure of any suitable description.

Mounting of the gas holder is preferably effected first erecting the supporting structure *b* and the bottom *a*. Then the top structure for 60 or of the bell is mounted over the bottom, and now the sheet-metal plates that are to form the wall of the bell are attached to said top structure ring after ring in downward direction, the bell being correspondingly lifted step by step 65 in correspondence with the progress of the work and being supported during the consecutive phases by brackets, such as *w* and *w*¹ in Fig. 9. Lifting of the bell correspondingly can be effected either by blowing it upwardly by filling it 70 with air or gas under pressure or by mechanical means. In either of these cases it is suited to the purpose to employ the guide tube *f* as a hoisting pole. To make these matters more clear I refer to Fig. 9 in which *a* denotes again the bottom, *b* 75 the supporting structure, *v* the packing means,

and *c*¹ the bell top to which the uppermost series of the sheet-metal wall members *c*² has already been affixed. The figure shows that state of the mounting procedure in which the second set *c*³ of the sheet-metal wall plates is to follow the 5 first. In order to render the mounting possible a scaffolding *u* is provisionally provided at the supporting structure *b*. When the plates *c*² and *c*³ have been connected with one another the finished part of the bell is lifted by as much as 10 corresponds to the height of the plates *c*³ and now the next series of the plates is connected with said latter plates, and so on.

I claim:

1. A bell gas holder comprising, in combination, 15 a stationary gas-tight bottom, means for supporting said bottom above a horizontal surface, a vertically movable bell arranged over the bottom in such a manner that the lower rim of the bell is lower than the border of the bottom so that the bell 20 confines such bottom, said bottom extending transversely to the vertical axis of the bell, sealing means at the rim of said bottom for sealing the gas holder at such place, and an open tube extending from the center of the bottom upwardly through the top of the bell for guiding the bell and communicating with the space between the bottom and said horizontal surface to ventilate the same.

2. A bell gas holder comprising, in combination, 30 a stationary gas-tight bottom, means for supporting said bottom above the ground, a vertically movable bell arranged over the bottom in such a manner that the lower rim of the bell is lower than the border of the bottom so that the bell 35 confines such bottom, said bottom extending transversely to the vertical axis of the bell, sealing means at the rim of said bottom for sealing the gas holder at such place, and a vertical member extending from the ground centrally through 40 the said bottom and through the top of the bell to guide the latter, said member being rigidly connected with the bottom so as to support it centrally.

3. A bell gas holder comprising, in combination, 45 a stationary gas-tight bottom, a vertically movable bell arranged over the bottom and of greater diameter than the bottom so as to confine the latter, said bottom extending transversely to the vertical axis of the bell, a structure supporting 50 the bottom above the surface of the ground at such a distance that when the bell is in its lowermost position, resting on the bottom, its lowermost edge is above the ground, so that the bell is at no time subjected to compressive stress due to 55 its weight, and a sliding seal at the rim of said bottom for sealing the gas holder at such place.

4. A bell gas holder comprising, in combination, 60 a stationary gas tight bottom, a vertically movable bell arranged over and above said bottom and confining the same in all operating positions of the bell, a structure supporting the bottom above the surface of the ground at a distance which is greater than the height of the bell, the 65 vertical wall of the bell thus being suspended from the top of the bell even in the lowermost position of the latter when it rests on the bottom, whereby the walls of the bell are at no time subjected to compressive stress due to its weight, and a 70 stationary sliding seal at the rim of said bottom and engaging the bell for sealing the gas holder at such place.

5. A bell gas holder as set forth in claim 3, including a vertical member extending from the 75

centre of said bottom upwardly through the top of the bell for guiding the bell in its vertical movements, and sealing means arranged between the top of the bell and the vertical member.

- 5 6. A telescoping bell gas holder comprising, in combination, a stationary gas-tight bottom, a vertically movable bell arranged over the bottom and of larger diameter than said bottom, said bottom extending transversely to the vertical axis 10 of the bell, an annular gas holder section between the bottom and the bell telescoping with the latter, said section being of a diameter intermediate that of the bell and bottom and thus confining said bottom, a structure supporting the bottom 15 above the surface of the ground at such a distance that when the bell is in its lowermost position its lowermost edge is above the ground so that the bell is at no time subjected to compressive stress due to its weight, and sliding seals between said bell, section and bottom, the seal between the

bottom and said section being attached to said bottom.

7. A gas holder comprising, in combination, a stationary gas tight bottom, a movable shell co-operating with said bottom to provide a storage space for gas and including a vertically movable bell arranged over said bottom and of greater internal diameter than the outer diameter of said bottom, said bell being thus adapted to confine such bottom, a structure supporting the bottom 10 above the surface of the ground at such a distance that when the bell is in its lowermost position, wherein it rests upon said bottom, its lowermost edge is above the ground, whereby the walls of the bell are at no time subjected to compressive 15 stress due to the weight of the bell, and a sliding seal located wholly inwardly of the bell and acting against the inner surface of the walls of the bell for sealing the gas holder at the bell.

KONRAD JAGSCHITZ. 20
